UNITED STATES PATENT OFFICE.

WILLIAM MORRISON, OF TROY, NEW YORK

MASSAGE SHAVING-BRUSH.

1,080,919.

Specification of Letters Patent.

Patented Dec. 9, 1913.

Application filed July 22, 1911. Serial No. 640,029.

To all whom it may concern:

Be it known that I, WILLIAM MORRISON, a citizen of the United States, and a resident of Troy, county of Rensselaer, and State of New York, have invented a certain new and useful Improvement in Massage Shaving-Brushes, of which the following is a full, clear, and exact specification.

This invention relates to a class of devices or brushes adapted particularly for use in conjunction with the work of shaving a person's face.

My invention has for its object primarily to provide an efficient device designed to facilitate the work of shaving a person's face, and wherein is employed a brush for applying the lather to the skin which is made of rubber or other flexible material instead of the usual form of brush made of hair; and to provide a brush which is adapted to be employed for softening the hair upon a person's face by a massaging process simultaneously with the application of the lather thereon.

65 A further object of the invention is to provide a shaving brush which is in the form mainly of an apertured hollow bulb for containing semi-liquefied or powdered soap which may be distributed upon the skin in required quantities by simply dipping the bulb in water and moving it to and fro over parts of the face until a proper lather is produced and the hair massaged until softened.

35 A practical embodiment of the invention is represented in the accompanying drawing forming a part of this specification in which similar characters of reference indicate corresponding parts in all the views, 40 the said invention being more fully described hereinafter and then pointed out in the appended claim.

In the drawing, Figure 1 is an elevation, partly in section, of one form of shaving brush embodying my invention. Fig. 2 is a view illustrating an elevation, partly in section, of the receptacle, or bulb used in the brush, and showing the handle thereof in section with its enlarged part removed therefrom, and Fig. 3 is a vertical section through the brush, with the enlarged part of its handle removed therefrom.

55 The shaving brush or device 10 has a hollow handle 11 which may be of any desired shape. One end of the handle 11 may be open, as 12, and in its other end may be a

plate 13 having a central opening 14, or upon the open end 12 of said handle may be an annular flange 15 which is preferably tapered or cone-shaped whereby an enlarged 60 open end, as 16, is provided.

Within the handle 11 and suitably held in the opening 14 of the plate 13 is one end of a tube 17 which may be threaded so as to be closed by a threaded cap or finger screw, 65 as 18. The tube 17 may be made of metal or other material or rubber and upon the opposite end of said tube is provided a hollow receptacle, or bulb 19 which forms the massage shaving brush proper. The 70 bulb 19 is made of rubber, or other flexible material, and is preferably oval or may be of any desired shape. When the tube 17 is made of metal the bulb 19 may be connected thereto in any suitable manner, or if said 75 tube is made of the same material as the bulb, the parts may be integrally formed, and the passage through the tube 17 communicates with the interior of the bulb 19 through the medium of an opening 20 80 formed in said bulb at its juncture with the tube. Upon a suitable portion of the exterior of the bulb 19 opposite to the opening 20 are provided a plurality of teats 21 made of rubber or other flexible material 85 instead of hair, and said teats are employed for spreading the lather over the skin in the well known manner at the same time serving to massage the skin and soften the hair thereon.

80 The bulb 19 is adapted to contain a required quantity of soap in a semi-liquid or powdered state, and a plurality of perforations 22 are provided in the wall of said bulb at spaced intervals between the teats 95 21 so that by exerting a slight pressure upon the bulb by means of the handle 11 in using the brush the soap will be forced through said perforations and converted to a lather of desired consistency by moistening the 100 teats with water.

In the foregoing description I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the 110 scope thereof.

Having thus described my invention, I

claim as new and desire to secure by Letters Patent:—

In a shaving brush, the combination of a hollow cylindrical handle provided with an open lower end and a closed upper end having an aperture therethrough communicating with the interior of the handle and a substantially spherical receptacle having walls of flexible material, with an elongated neck at its upper portion projecting through the aperture in the upper end of the handle and having a removable cap for closing the end thereof, and retaining the parts in proper position, said receptacle being dis-

posed within and partially inclosed by the open end of said handle and closely engaging the inner wall thereof and having on its lower hemispherical surface a plurality of projections and having apertures through the walls thereof between said projections, substantially as and for the purposes set forth.

This specification signed and witnessed this twenty first day of July A. D. 1911.

WILLIAM MORRISON.
